UNITED STATES PATENT OFFICE.

FRED. L. PERKINS, OF SAN BERNARDINO, CALIFORNIA.

LOCOMOTIVE SMOKE DEFLECTOR.

Application filed June 26, 1922. Serial No. 571,015.

To all whom it may concern:

Be it known that I, FRED. L. PERKINS, a citizen of the United States, residing at San Bernardino, in the county of San Bernardino and State of California, have invented certain new and useful Improvements in Locomotive Smoke Deflectors, of which the following is a specification.

My invention relates to improved smoke deflecting devices, and is particularly designed for use in connection with the smoke stack of a steam locomotive, but is applicable to use in other ways. It is the principal object of my invention to provide improved means for moving the deflector into and out of operative position.

That which I believe to be new and desire to cover by Letters Patent is set forth in the claims.

20 In the drawings—

Fig. 1 is a side view of a locomotive, partly broken away, equipped with my improved smoke deflecting means, a changed position of the deflector being shown in dotted lines.

Fig. 2 is a rear view of the smoke deflector, being substantially a section taken on line 2—2 of Fig. 1.

Fig. 3 is an enlarged detail view, being a section taken on line 3—3 of Fig. 2.

Fig. 4 is an enlarged detail view, taken substantially on line 4—4 of Fig. 1.

Fig. 5 is an enlarged detail view of the connection between the piston rod and the belt employed for moving the deflector out of operative position.

Fig. 6 is a horizontal sectional view, taken on line 6—6 of Fig. 1.

Fig. 7 is a vertical section through the controlling valve of the power means for throwing the deflector out of operative position; and

Fig. 8 is a top plan view of the valve plug.

Referring to the several figures of the drawing, in which corresponding parts are indicated by the same reference characters: 15 indicates a locomotive boiler, with a smoke stack 16 rising therefrom, and with a cab 17 of any approved type located near its rear end. As is best shown in Fig. 6, a two-part ring 18 is secured by means of bolts 19 about the stack 16, one of the parts of the ring being provided with arms 20 in the outer ends of which a shaft 21 is revolvably mounted. 22 indicates a deflector

in the form of a curved hood or elbow formed of sheet metal and of a size adapted to fit loosely about the upper end of the stack 16, preferably in contact with the ring 18 as shown in Fig. 2. The deflector 22 is provided with arms or sectors 23 welded or otherwise firmly secured thereto, the outer ends of the arms 23 being mounted upon the shaft 21 to which they are rigidly secured in any suitable manner. As is best shown in Fig. 1, the deflector 22 is given a backward curvature, so as to direct the smoke and hot gases from the stack 16 rearwardly in a substantially horizontal direction. The deflector, however, is of substantially the same size as that of the stack 16, whereby the hot gases coming from the stack are not permitted to expand to any appreciable extent within the deflector, but are directed backwardly so as to pass directly over the cab 17 at the rear of the locomotive, the deflector being free of any means which would have any material tendency to cut down the velocity of movement of the hot gases.

For holding the deflector 22 positively in position upon the upper end of the stack 16, and for moving it alternatively out of operative position upon the stack, I have provided a drum or pulley 24, fixedly mounted upon one end of the shaft 21, together with means for giving said drum a rotary movement as may be desired. This rotating means comprises a flexible connector 25 extending about idler pulleys 26 and 27, and having its ends wrapped about the drum 24, and fixedly secured thereto, as at the points 28 and 29, as illustrated in Fig. 3. The idler pulley 26 is preferably adjustable forwardly and backwardly by means of a screw 30, as is illustrated in Fig. 1. As will be readily understood, when the flexible connector or cable 25 is moved alternatively in opposite directions, the deflector 22 will be swung alternatively into and out of operative position, as shown in solid lines in Fig. 1, about the rock shaft 21.

For moving the flexible connector 25 for carrying the deflector into and out of operative position, I have provided a cylinder 31 fixedly mounted upon the boiler 15 in rear of the stack 16. Within the cylinder 31 is located a piston 32 provided with a piston rod 33, the outer end of which is connected by means of a suitable clip 34 with the flexible connector or cable 25. As is best

shown in Fig. 5, the clip 34 is formed of two parts, one of which is secured by means of screw threads upon the front end of the piston rod 33, and the other of which is in the form of a plate 35 secured by means of screws 36, so as to grip the cable 25. For operating the piston 32, I have connected the cylinder 31 with a suitable source of air, steam or other fluid under pressure, such connection being effected by the use of pipes 37 and 38, which are connected in turn through a valve 39 with a pipe 40 leading from the source of the fluid under pressure.

As will be readily understood, the valve 39 may be of any approved type which will permit the fluid under pressure from the pipe 40 to be fed alternatively through the pipes 37 and 38, the arrangement being such that when one of said pipes is connected for receiving the fluid under pressure, the other pipe is open so as to permit the exhaust from the opposite end of the cylinder 31. In the construction shown in Figs. 7 and 8, the valve comprises a valve plug 41 provided with a peripheral groove 42 and a transverse opening 43 by which the air is admitted alternatively through the pipes 38 and 37, respectively. Radially disposed exhaust ports 44 and 45 are provided leading to a central bore 46. The valve plug 41 is provided at its outer end with a handle 47 by means of which the desired rotary movement can be given to the valve plug for effecting the desired control, as will be readily understood.

As is shown in Fig. 1, the valve 39 is preferably located within the cab 17, so as to be readily accessible to the train crew.

As will be readily understood, when the deflector 22 is in operative position, as shown in Fig. 1, it is held in such position by the pressure of the air or other fluid upon the forward face of the piston 32. When it is desired to move the deflector out of operative position into the position shown in dotted lines in Fig. 1, it is only necessary that the valve plug 41 be given a movement in clockwise direction, into the position shown in Fig. 7, so as to connect the rear end of the cylinder 31 with the source of air under pressure, and to connect the front end of the cylinder with the exhaust ports of the valve 39. The piston 32 is then moved forward, so as to cause the drum 24 to revolve in clockwise direction, as shown

in Fig. 1, so as to carry the deflector backwardly and downwardly about the rock shaft 21.

While I prefer to employ the form of structure illustrated in the drawings, and above described, it will be understood that I do not wish to be limited to the details of such construction, except as hereinafter specifically claimed, inasmuch as it is evident that many changes can be made without departing from the spirit of my invention.

I claim:

1. The combination of a smoke stack, a deflector pivotally mounted on the stack for directing the smoke in a substantially horizontal direction, a drum rotatable with said deflector about its pivotal mounting, a flexible connector extending about said drum, and means for moving said flexible connector in opposite directions for rotating said drum and said deflector for moving the deflector into and out of operative position above said stack.

2. The combination of a smoke stack, a rock shaft revolvably mounted thereon, a deflector fixedly mounted on said rock shaft and movable thereon into and out of position above the stack for directing the smoke in a substantially horizontal direction, a power wheel fixedly mounted on said rock shaft, a cylinder, a piston in said cylinder, operative connections between said piston and said power wheel adapted for giving said wheel a rotary movement upon a stroke of the piston in either direction serving to move said deflector into and out of operative position on said stack, and means for feeding fluid under pressure to said cylinder for giving said piston alternate strokes in opposite directions.

3. The combination of a smoke stack, a deflector pivotally mounted on the stack for directing the smoke in a substantially horizontal direction, a drum rotatable with said deflector about its pivotal mounting, a flexible connector wrapped about said drum and having both ends secured to the drum, idler pulleys associated with said drum for supporting said flexible connector, and power means connected with said flexible connector for moving it alternately in opposite directions for rotating said drum and said deflector about their pivotal mounting for moving the deflector into and out of operative position above said stack.

FRED. L. PERKINS.
